COMBINATION SHOVEL AND CHAIR

Alfred E. Pickard, Mount Vernon, Ill.

Application April 22, 1939, Serial No. 269,379

7 Claims. (Cl. 155—143)

This invention relates to a combination shovel and chair, or chair attachment for shovels either full size for practical purposes or miniature for souvenir or advertising purposes.

The principal object of the invention is to provide a shovel with a seat or chair attachment, which by using the shovel in an inverted position will be converted into a chair.

A further object is to provide a novel combination shovel and chair in which the shovel has combined therewith a few simple parts capable of very economical production and convenient application to the shovel, to provide means whereby a comfortable seat or chair is produced, and which can be easily removed if desired or adjusted to a position, whereby the shovel may be used alone for its ordinary intended purposes.

Another object is to provide a novel construction of seat or chair, in which the handle and blade or scoop of the shovel form attaching means for the seat and a brace with which the blade or scoop cooperates to produce another brace, leg or support, and in which the handle forms a back for the chair.

Further objects and advantages will appear and be brought out more fully in the following specification, reference being had to the accompanying drawing, in which:

Fig. 1 is a perspective view of my combination shovel and chair or chair attachment for shovels;

Fig. 2 is a side elevation enlarged;

Fig. 3 is an elevation, looking in the direction of the line 3—3 of Fig. 2;

Fig. 4 is a section on line 4—4 of Fig. 2;

Fig. 5 is a fragmentary view similar to Fig. 2 of a modification;

Fig. 6 is a side elevation thereof held in folded position; and

Fig. 7 is a fragmentary plan view taken on line 7—7 of Fig. 5.

Referring more particularly to the drawing, 18 designates a shovel of full size for practical purposes or for children, or in miniature for souvenir or advertising purposes having or comprising the usual handle 11 with a hand gripping portion 12 and a blade or scoop 13 in obtuse angled relation to the handle. The blade preferably has a straight back edge 14 extending outwardly substantially at right angles to the length of the handle and a shank or sleeve 15 forming a socket in which the shank or lower end of the handle is fastened as by transverse diametrical rivets 16. Of course, the handle, instead of being of wood or separate from the blade or scoop and shank 55

socket or sleeve of the shovel, may be of metal or integrally or otherwise formed.

The blade or scoop adjacent to the back edge may be provided with two or more holes 17 for connection of a seat 18 therewith. This seat of wood or otherwise, may or may not have a recess, groove or notch 18a to engage the handle 11 and to bear thereon against lateral displacement and to center the seat on the shovel. The seat is fastened on top at its back edge intermediately thereof directly to the handle and hinged at 20 at the front edge on the bottom or underneath the seat to a brace 21 comprising spaced parallel legs.

Brackets 22 are provided to connect the legs of the brace 21 to the blade 13, said connection being detachable and the brackets comprising metallic plates or straps having offset pins or reduced downwardly extending ends 23 detachably engaging the holes 17 and having shoulders 24 at the offset or angular portions of the brackets 22 to contact or engage the back face of the shovel blade or scoop to limit the displacement of the pins therein and give support as well as to prevent angular movement of the connected parts relatively. The brackets 22 may be secured in position to the brace or legs 21 as by bolts, screws or other fasteners 25 and the legs are connected by a cross brace 26 near the lower ends or feet 30 thereof to give a rigid support structure.

The hinges 20 each comprise pivoted leaves 27 and 28, the former being bolted or otherwise fastened to the brace legs 21 at 29, and the latter to the underside and front edge of the seat 18 at 30, with the heads of the bolts or screws preferably countersunk to avoid projections likely to catch in one's clothing. The hinge 19 has a leaf 31 bolted or otherwise fastened to the seat 18 on top and adjacent to its back edge as at 32 with the pivot or pintle between the seat edge and handle 11 so the seat can swing up, against or toward the back of the handle from the position shown in Figs. 1 to 5 inclusive to the position shown in Fig. 6, while the brace or legs 21 move therewith in an arc and longitudinally, to disengage the pins 23 from the holes 17 and the feet ends of the legs or brace 21 move into, against and on the top and front of the blade or scoop 13 of the shovel as shown in Fig. 6 and over the shank of the handle until the cross brace 26 engages the latter and forms a stop or limiting member.

The pivotal connection of the seat 18 at the hinge 19 with the handle 11 may be detachable by an ordinary hinge leaf with screws or by a split sleeve or clamp 33 with upper and lower semi-

circular jaws 34 and 35 respectively, hinged together longitudinally or in the direction of the length of the handle 11 and substantially parallel thereto at one side of the handle as at 36. These jaws envelop and fit the handle 11 above the sleeve 15, and are provided with apertured ears 37 and 38 to take a bolt 39 engaged by a wing nut 40 to firmly clamp the handle 11 and connect the seat 18 at the rear edge thereof and hinge 19 to the handle but permit convenient disconnection thereof to remove the seat from the shovel or collapse the same therewith as previously explained.

When the seat is in position for use, a chair is formed, the shovel being inverted in position relative to that when in use as a shovel, the brace or legs 21 crossing the shovel at the sleeve or shank 15 above and at the back edge of the blade or scoop 13 so that the pins 23 can engage the holes 17 with the upper part of the brace 21 extending above and forwardly. In this position, 20 the seat 18 is opened out from the folded position shown in Fig. 6 and extended horizontally rearwardly as seen in Figs. 1, 2, 3 and 5, to the upwardly and rearwardly extending handle 11 where it is pivotally attached by the hinge 19 and clamp 33. The part of the handle extending above the seat 18 forms a reclining back for the chair and the angle of inclination will vary with different types of shovels or spades. In full size, the device forms a comfortable seat, but it may be made in 30 miniature for souvenir or advertising purposes.

In the modification shown in Figs. 5, 6 and 7 of the drawing means are provided to hold the chair folded against the shovel if disconnection or complete physical separation is not desired. 35 While any suitable means may be provided for this purpose, the leaf 31 is provided with a lateral trunnion or apertured lug 41 to detachably pivot a hook 42 which may be accommodated in a depression or recess in the top of the seat. This hook is designed to engage an apertured lug 43 extending upwardly from the end or top edge of the ear 37 as seen in Fig. 6 to hold the parts securely folded as heretofore explained and permit use of the shovel.

While I have illustrated and described two preferred forms of construction for carrying my invention into effect, this is capable of variation and modification without departing from the spirit of the invention. I, therefore, do not wish 50 to be limited to the precise details of construction set forth, but desire to avail myself of such variations and modifications as come within the scope of the appended claims.

Having thus described my invention, what I 55 claim as new and desire to secure by Letters Patent is:

1. A chair attachment for shovels including a seat having means for pivotal connection at one end with the back of the handle of the shovel and a brace pivotally connected to the other end of

the seat and having means near the upper end thereof to engage and rest on the back of the blade of the shovel.

2. A chair attachment for shovels having a handle and a blade, including a seat having means for pivotal connection with the handle and extending from the back thereof and a brace pivotally connected to the other end of the seat and having means of detachable connection with the blade of the shovel at the back edge thereof and adapted to fold upwardly with the seat toward the underside of the handle, said brace when in supporting position crossing the handle in divergent relation to the blade to support the structure when used as a chair.

3. The combination with a shovel having a blade and a handle, a brace adapted for detachable connection with the blade, and a seat pivoted to the brace and having means of pivotal and detachable connection with the handle.

4. In combination with the handle and blade of a shovel, a brace adapted for detachable connection with the back edge of the blade and crossing the shovel to form a support in connection with the blade, a seat connected to the upper end of the brace to extend horizontally and rearwardly to the handle, and means to connect the rear edge of the seat to the handle between its ends.

5. In combination with the handle and blade of a shovel, a brace adapted for detachable connection with the back edge of the blade and crossing the shovel to form a support in connection with the blade, a seat pivotally connected to the upper end of the brace to extend horizontally and rearwardly to the handle, means to pivotally connect the rear edge of the seat to the handle between its ends, said parts being foldable, and means to hold the seat in folded relation to the shovel.

6. In combination, a shovel having a handle and a blade, the blade having holes near its back edge, a brace having lugs to engage the holes and to cross the handle adjacent the back edge of the blade, said brace and blade forming chair supporting legs, a seat hinged to the upper end of the brace and a clamp pivoted to the rear edge of the seat to detachably connect the same to the handle with a portion of the handle projecting thereabove.

7. A chair attachment for a shovel, including a seat having means for pivotal connection with the handle of the shovel and a brace connected to the front edge of the seat and detachably connected to the blade, crossing the handle in divergent relation to the blade and handle to form a supporting structure in connection with the blade of the shovel, said handle forming a back for the seat.

ALFRED E. PICKARD.
